Application March 11, 1946, Serial No. 653,553

3 Claims. (Cl. 121—38)

1

This invention relates generally to fluid pressure actuated devices and is especially adaptable, among other uses, for hydraulic ram mechanisms for urging a tool against or through a workpiece.

Primary objects of this invention are to provide a novel and improved ram mechanism of the class described; to provide in such a mechanism novel means for guiding the tool-carrying portion; to provide means whereby the rate of movement of the tool-carrying member may be controlled; to provide in such a fluid-actuated ram means a construction whereby any leakage flow of fluid past the movable members is conducted back to the source of supply; to provide a multiple piston arrangement whereby greater force may be exerted upon the carried tool with a small over-all dimension; to provide a ram mechanism which carries a plurality of tools whereby a first tool can engage the work and thereafter a second tool can engage the work; and to provide a small, compact ram mechanism which can be suitably arranged in multiple banks for performing a multiplicity of simultaneous or sequence operations on a member or workpiece by means of inexpensive jigs, thereby eliminating the cost of larger equipment and costly dies. Other objects will be apparent from the specification, drawings, and appended claims.

In the drawings, in which like numerals are used to designate like parts in the several views throughout,

Fig. 1 is a view in central vertical cross section of a ram mechanism embodying the invention;

Fig. 2 is a view in end elevation showing the device of Fig. 1;

Fig. 3 is a view in side elevation of the ram mechanism shown in Fig. 1 mounted on a supporting member for punching a workpiece, the workpiece and its carrying portion being shown in cross section;

Fig. 4 is a view in side elevation of a ram mechanism similar to that of Fig. 1, showing an adapter plate carried thereby arranged for drilling; and,

Fig. 5 is a view in side elevation showing the ram mechanism similar to that of Figs. 1 and 4, but having an adapter plate arranged for milling.

Referring to the drawings, the numeral 1 designates generally a platelike base member hav-

2

ing an integral laterally extending, platelike member 2 having an aperture 3 extending therethrough, the longitudinal center line of which extends substantially parallel to the top face 4 of the base member 1. The member 1 has a plurality of countersunk holes 5 which receive suitable cap screws for securing the base member 1 to a support 6 when it is desired to rigidly hold the plate member 1 with respect to the support 6. As shown in Fig. 3 it is sometimes desirable to permit movement between the platelike member 1 and the support 6, and in this event no cap screws are used in the apertures 5, the platelike member 1 being carried by the support 6 in slide members 7 extending over flanges 8 of base member 1. The slide members 7 are suitably secured to the support 6 by stud bolts 9. In this construction a strap member 10 is secured to one end portion 12 of the base member 1 by stud bolts 14. A stud screw 16 screw-threaded into the support 6 extends through an aperture in the strap member 10 and therebeyond. Preferably the stud screw 16 is locked in the support 6 by means of a nut 18. A helical coil compression spring 20 concentric with screw 16 has one end portion abutting the strap member 10 and its other end portion abutting the under side of a pair of locking nuts 22 secured to the portion of the stud screw 16 extending beyond the strap member 10. The spring 20 acts against the strap member 10 and therethrough to urge the base member 1 in a downward direction as seen in Fig. 3, to cause the tool 24 carried by a laterally extending portion 26 of the base member 1 to be moved out of engagement with the workpiece 28. Movement of the base member 1 by the spring 20 is limited by engagement of the strap member 10 with a second pair of locking nuts 30 carried by the stud screw 16 intermediate the nuts 18 and the strap member 10.

Referring again to Fig. 1 the ram mechanism comprises a first cylinder member 32, a piston member 34, an outer sleeve 36, and an adapter plate 38 for carrying a tool, such as tool 39 of Fig. 3. The cylinder member 32 has a normal diameter portion 40 and a reduced diameter portion 42 which substantially conforms to the aperture 3 and is received therein. A shoulder 44 formed at the intersection of the normal diameter

portion 40 with the reduced diameter portion 42 seats against the front face 46 of the laterally extending portion 2 of the base member 1. The reduced diameter portion 42 extends through and beyond the opposite or rear face 47 of the laterally extending portion 2 and is externally screwthreaded for reception of an internally screwthreaded nut 48 which abuts the face 47 for clamping shoulder 44 of the cylinder member 32 tightly against the face 46 whereby member 32 is rigidly carried by the laterally extending portion 2. The portion of the cylinder member 32 extending away from the portion 2 on the side of face 46 has a piston chamber 50 opening outwardly through the extending end portion 52 of the cylinder member 32 in which the head 54 of the piston 34 has a piston-tight fit. A hollow stem portion 56 of piston 34 extends longitudinally of the chamber 50 and outwardly through the end portion 52 of the cylinder member 32 and is received within a recess 55 in a cylindrical projecting portion 57 on the adjacent wall of the adapter plate 38. The piston head 54 has a series of counterbores forming a shoulder 58 against which an apertured plate 60 is positioned. A series of radially positioned apertures 62 and a central aperture 64 which is concentric with the hollow interior of the piston stem 56 extend through plate 60. A cap screw 66 extending through aperture 64 has its head portion engaging the aperture plate 60 and its other end portion screwthreaded into the adapter plate 38 for holding the adapter plate 38 rigid to the piston 34 and the plate 60 against shoulder 58.

The outer sleeve 36 telescopically surrounds the cylinder member 32 and has one end surface 67 thereof adapted to abut the face 46 of the laterally extending portion 2 of the base member 1, thereby limiting its movement in a tool retracting or one direction on the cylinder member 32. The other end 68 of the outer sleeve 36 extends beyond the extending portion 52 of the cylinder member 32 and is received about the cylindrical projecting portion 57 of the adapter plate 38. The portion 68 is preferably secured to the plate member or adapter plate 38 in a fluid-tight manner, such as by welding, as at 70. The cylinder member 32 has a longitudinally extending circumferentially recessed portion 72 which, in part, is coextensive with the piston chamber 50, and, at all normal positions, the sleeve 36 surrounds portion 72 to form a chamber 74. Radially extending passageways 76 positioned at spaced points in member 32 communicatively connect the piston chamber 50 with the chamber 74 for fluid flow therebetween.

The stem portion 56 adjacent the cylinder member portion 52 is guided within an annular member 78 having its external surface substantially fitting the inner surface of the piston chamber 50 and having its inner surface substantially fitting the external surface of the piston stem portion 56. Snap rings 80, fitting in recesses in the wall of chamber 50, hold the member 78 in fixed position. Undesired fluid flow between the cylinder member 32 and annular member 78 is prevented by a piston ring or gasket 82 which is received within a circumferential recess of the annular member 78. The cylindrical portion 51 of adapter plate 38, the adjacent portion of the outer sleeve 36, the extending end wall of the cylinder member 32, and the annular member 78 cooperate together to provide an expansible-contractible chamber 84 which at all times is in fluid-flow communication with the hollow interior of the stem portion 56 by means of radially

extending passageways 86 through the wall of the piston stem portion 56. These passageways 86 are so positioned longitudinally of the stem 56 that they remain at all times on the side of the annular member 78 adjacent the chamber 84.

A radially extending passageway 88 extends through the side wall of the piston stem portion 56 and communicatively connects, for fluid flow, the hollow interior of the stem portion 56 with an annular chamber 90 formed around portion 56 within the piston chamber 50 intermediate the annular member 78 and the piston head portion 54. The passageway 88 is so positioned longitudinally of the stem portion 56 that, with the surface 67 of the outer sleeve 36 in engagement with the surface 46, the passageway 88, at least partially, maintains communication between the chamber 90 and the hollow interior of the stem portion 56. Upon predetermined movement of the adapter 38 away from the cylinder member 32, the passageway 88 will pass into the annular member 78 thereby co-operating with the stem portion 56 in the manner of a slide valve to stop fluid-flow through the passageway 88. The cylinder member 32 on either side of the recess portion 72 has outwardly opening circumferentially extending recesses 92 which receive piston rings or packing to resist undesired fluid-flow thereby between the cylinder member 32 and the outer sleeve 36.

Fluid under pressure pumped from a suitable source of supply (not shown) is conducted by means of a conduit 93, passageway 93a in the rotatable portion 94 of valve 91, and conduit 95, to a passageway 96 extending concentrically and longitudinally of the cylinder member 32 and opening through an end wall 97 into a pressure chamber 51 formed in chamber 50 intermediate the wall 97 and piston head 54. A second longitudinally extending passageway 98 extends substantially parallel with the passageway 96 and opens through a radial passage 98'. Passageway 98 also opens into a circumferentially arranged annular chamber 99. The laterally extending portion 2 of the base member 1 has a passageway 100 which aligns with the circumferential annular chamber 99 and is screwthreaded for reception of a discharge conduit 104 for conducting fluid from the passageway 98. Conduit 104 is connected to valve 91 and, by means of passageway 104a in valve portion 94, to a return conduit 105 which may open into the source of fluid from which the conduit 93 is supplied. A third conduit 106 communicatively connects the valve 91 with the passageway 98 so that when the valve portion 94 is moved to a second position a valve passageway 106a in portion 94 will communicatively connect conduits 93 and 106 for flow of pressure fluid to chambers 74 and 90. The second position 60 of valve portion 94 also aligns valve passageway 105a with conduits 95 and 105 for fluid flow from chambers 51 and 84 to the source of fluid supply. The valve portion 94 may be rotated from the first position, as shown in Fig. 1, to the said second position by handle 107 which is engageable with stops 108 and 109 to limit rotational movement so that the proper passageway 93a, 104a or 105a, 106a will be aligned with conduits 93, 95 and 104, 105 or 95, 105 and 93, 106 as described above for the shown and the said second position of the valve portion 94. Lines 93 and 105 may, of course, be associated with any suitable supply system, utilizing pumps or other devices having characteristics suited to the work.

75 A guide dowel pin 110 carried by the adapter

plate 38 extends toward and is received within a guide aperture 111 of the base member 1. In the modification shown in Fig. 5 two such pins 110 and apertures 111 are illustrated. The pins 110 and apertures 111 cooperate with the telescopic arrangement of sleeve 36 with cylinder member 32 to provide guiding means for the adapter 38 which accurately holds the adapter 38 against all undesired movement so that the tool 39 may do accurate work on the workpiece 28.

The adapter plate 38 may be arranged to carry a variety of tools for operating on a workpiece. In Fig. 3 there is shown a set of tools 24 and 39 for forming and punching the workpiece 28. In Fig. 4 the adapter plate 38' is arranged to carry multiple drill spindles 112 which may be rotated by a motor 113 (electric, fluid or other type) carried by the adapter plate 38'. In Fig. 5 the adapter plate 38'' is shown as carrying a milling cutter 114 which may be rotated or powered by a similar motor 115 also carried by the adapter plate 38''. In the arrangements shown in Figs. 4 and 5 it is often desirable to provide means whereby the adapter plates 38' and 38'' are moved relatively slowly and with less force until the drill carried by the multiple drill spindle 112 or the milling cutter wheels carried by the milling cutter 114 are in engagement with the work and thereafter to apply the full fluid force to hold the drills and milling cutters against the workpiece. This rate of change of speed and force exerted by the ram is provided for by regulating the rate of fluid flow through conduit 104 by means of a valve member 116 carried within the plate-like member 2' and cooperable with a valve seat 117. The valve member 116 is urged away from seat 117 and into engagement with a cam track 118 of cam member 119 by a spring 120 concentric with member 116 and held between valve member flange 121 and the bottom wall of the valve chamber 122. The member 119 is reciprocally movable within an aperture 123 extending through the member 2' and a threaded end portion 124 received within an aperture 125 of a laterally extending portion 126 of the sleeve 36. Pairs of nuts 127 and 128 threaded onto portion 124 provide spaced abutments engageable by portion 126 for longitudinal movement of the member 119. These may be arranged as shown to provide lost motion or may clamp the member 119 tightly to the sleeve portion 126. By changing the contour of cam track 118 other desired rates of movement may be provided for, it being understood, of course, that junctions between successive tract portions are sloped sufficiently to permit camming movements of the stem of valve 116. This restriction of fluid-flow (which, preferably, is utilized only in the presence of relatively low pressures in the inlet line 96), to the conduit 104 acts to set up a back pressure against the piston head 54 to effectively reduce the force exerted by the incoming fluid pressure through the passageway 96 and acting intermediate the piston head 54 and wall 97 for moving the tools against the workpiece.

A U-shaped guard ring 130 is carried by the base member 1 and its laterally extending portion 2 by means of screws 132 so that as the end of the outer sleeve 36 moves away from the surface 46, no foreign matter can drop into the space vacated by the outer sleeve 36 and upon return movement of the sleeve 36 into engagement with the surface 46 be crushed therein and cause damage.

The operation of the hydraulic or fluid-pressure ram is as follows: Fluid pressure pumped from a suitable source of supply (not shown) is

forced through conduit 93 and controlled by valve 91 to flow either into conduit 95 or 106. In the position shown fluid flows through passageway 93a, conduit 95, passageway 96, and into the chamber 51 intermediate the end wall 97 and the piston head 54. Fluid also flows through the apertures 62 of the apertured plate 60 through the hollow stem 56 and through the radial passageway 86 into the chamber 84. With the elements positioned as shown in Fig. 1, fluid also flows through the radial passageway 88 into the chamber 90 and therefrom to the radial passageway 76 into the chamber 74, out through the passageway 98, conduit 104, passageway 104a and the conduit 105. Normally, the chambers 50 and 84 will be filled with fluid and as fluid is supplied by conduit 93 a pressure builds up in chambers 51 and 84 in a direction to force the adapter plate 38 outward from the base portion 1. A certain amount of fluid flows through passageway 88 thus increasing the pressure in chamber 90 at the same time the pressures are building up in chamber 51 and 84 thereby creating a back-pressure against the back side of the piston head 54, which tends to oppose the effect of the fluid pressure in chamber 51. Simultaneously with the foregoing, some fluid flows outwardly from the chamber 90 through the passageway 76, into the chamber 74, and therefrom through the passageway 98 into the conduit 104. As soon as the piston 34 has moved outwardly a short distance, the passageway 88 is closed because it then registers with the annular member 78 and no more fluid flows from the stem portion 56 into the chamber 90.

It will now be noted that fluid pressure in the chamber 51 acts in effect on the full area of the head 54 although some of it may act down through the hollow stem against the bottom of the recess 55 of the adapter 38. In addition, the fluid pressure acts on the remainder of the raised portion 57 of the adapter plate 38 and has an effective acting area in the form of an annulus (equal in area to the area of the face of boss 57 less the area of the reduced portion 56 of piston 34) which supplements the force acting upon the piston head 54. To move the tool away from the workpiece the handle 107 of valve 91 is moved into engagement with stop 109 which rotates valve portion 94 to bring passageway 105a into alignment with conduits 95 and 105 and passageway 106a into alignment with conduits 93 and 106. Fluid under pressure from conduit 93 flows through passageway 106a, conduit 106, passageway 98, chamber 74, and passageways 76 to chamber 90 to exert a force on piston head 54; passageway 88 being closed by member 78. Chambers 84 and 51 at this time are open to tank through passageways 96 and 105a and conduits 95 and 105 so that fluid in chambers 51 and 84, displaced by the tool retracting movement of piston 34 and adapter 38, will flow back to the tank. It should be noted that flow of fluid from passageway 98 to the supply source flows through conduit 104 which may be provided with the restrictor valve 116; however, fluid flow to passageway 98 from the source of supply is through conduit 106 which has no such restrictor.

At or near the conclusion of the retracting stroke, stem 56 exposes port 88, completing a by-pass connection around chamber 90, leading to the tank, and extending through the bore of stem 56, chamber 51, and passageway 96. It will be appreciated that this by-pass connection 75 governs the pressure at which the adapter 38 is

retained in retracted position, thereby reducing the pressure demand on the source during stand-by periods and also reducing power requirements. Further, and, importantly, this by-pass connection permits a continuous circulation of oil from the source throughout the device. This continuous circulation, as will be understood, cleanses the oil.

Referring to the apparatus as shown in Fig. 3, the adapter plate 33 carrying the tool will be moved relative to the supporting plate 1 into engagement with the workpiece 28 as described hereinbefore. Subsequent to engagement with the workpiece 28 the reaction force exerted by the tool 24 on the workpiece 28 will overcome the opposing force of the spring 20 and the plate member 1 will bodily slide in the ways or slide members 7 whereby the tool 24 carried by the member portion 23 will move into engagement with the workpiece 28, and in the instance shown in the subject figure will cause the tool 24 to pierce the workpiece 28. Subsequent to release of pressure in the conduit 35, the spring 20 will act against the strap member 10 forcing the plate member 1 downwardly and the tool 24 out of the workpiece 28.

This invention provides an improved ram mechanism simple and economical of construction, which construction provides an effective piston area greater than the cross-sectional area of the ram cylinder whereby greater forces may be exerted by the ram; means whereby the rate of movement of the tools may be controlled as well as the force exerted by the tools on the workpiece; a simple, small, compact ram which may be used in multiple banks, thereby doing away with costly cam dies, and which may be operated from a common fluid pressure supply line along with other mechanism without requiring special individual fluid pressure control valves otherwise necessary so that the tools do not exert too great a force on the workpiece or impinge thereon with a too great striking force.

What is claimed and is desired to be secured by United States Letters Patent is as follows:

1. In a pressure-operated ram mechanism, a plate-like base having a platelike portion extending laterally thereof, said portion having an aperture opening through one face thereof, a cylindrical member having a portion held within said aperture, said cylindrical member having a piston chamber therein opening through one end wall thereof and having a pair of passageways opening outwardly through another wall thereof, one of said passageways communicating with said chamber adjacent one end thereof, said cylindrical member having a reduced diameter outer peripheral portion, the other of said pair of passageways communicating with said peripheral portion, a piston having a head portion positioned within said cylindrical member and having a hollow stem portion extending outwardly of said end wall, an adapter, means securing said adapter to said stem portion, a sleeve telescoping over said cylindrical member, one end of said sleeve being secured to said adapter, the other end portion of said sleeve extending beyond said peripheral portion to form an outlet chamber and toward the other end portion of said cylindrical member whereby said sleeve is guided at spaced points for reciprocal movement longitudinally thereof, said cylindrical member having a passageway leading from said piston chamber adjacent said cylindrical member one end wall and opening into said outlet chamber, means surrounding said stem portion intermediate said last-named passageway and said cylindrical member one end wall and co-operable with said cylindrical member to guide said stem portion, said stem portion having a passageway opening from the hollow interior thereof and positioned longitudinally of said stem portion so that at one position of said piston said stem portion passageway opens into said outlet chamber, the longitudinal position of said stem passageway being such that upon movement of said piston in one direction said stem portion passageway is closed by said surrounding means, and means for conducting fluid from the portion of said piston chamber which is intermediate said head portion and said chamber one end to the hollow interior of said stem portion, and means controlling fluid flow through said other of said pair of passageways.

7. In a pressure-operated ram mechanism, a plate-like base having a platelike portion extending laterally thereof, said portion having an aperture opening through one face thereof, a cylindrical member having a portion held within said aperture, said cylindrical member having a piston chamber therein opening through one end wall thereof and having a pair of passageways opening outwardly through another wall thereof,

rounding said stem portion intermediate said last-named passageway and said cylindrical member one end wall and co-operable with said cylindrical member to guide said stem portion, said stem portion having a passageway opening from the hollow interior thereof and positioned longitudinally of said stem portion so that at one position of said piston said stem portion passageway opens into said outlet chamber, the longitudinal position of said stem passageway being such that upon movement of said piston in one direction said stem portion passageway is closed by said surrounding means, and means for conducting fluid from the portion of said piston chamber which is intermediate said head portion and said chamber one end to the hollow interior of said stem portion.

2. In a pressure-operated ram mechanism, a platelike base having a platelike portion extending laterally thereof, said portion having an aperture opening through one face thereof, a cylindrical member having a portion held within said aperture, said cylindrical member having a piston chamber therein opening through one end wall thereof and having a pair of passageways opening outwardly through another wall thereof, one of said passageways communicating with said chamber adjacent one end thereof, said cylindrical member having a reduced diameter outer peripheral portion, the other of said pair of passageways communicating with said peripheral portion, a piston having a head portion positioned within said cylindrical member and having a hollow stem portion extending outwardly of said end wall, an adapter, means securing said adapter to said stem portion, a sleeve telescoping over said cylindrical member, one end of said sleeve being secured to said adapter, the other end portion of said sleeve extending beyond said peripheral portion to form an outlet chamber and toward the other end portion of said cylindrical member whereby said sleeve is guided at spaced points for reciprocal movement longitudinally thereof, said cylindrical member having a passageway leading from said piston chamber adjacent said cylindrical member one end wall and opening into said outlet chamber, means surrounding said stem portion intermediate said last-named passageway and said cylindrical member one end wall and co-operable with said cylindrical member to guide said stem portion, said stem portion having a passageway opening from the hollow interior thereof and positioned longitudinally of said stem portion so that at one position of said piston said stem portion passageway opens into said outlet chamber, the longitudinal position of said stem passageway being such that upon movement of said piston in one direction said stem portion passageway is closed by said surrounding means, and means for conducting fluid from the portion of said piston chamber which is intermediate said head portion and said chamber one end to the hollow interior of said stem portion, and means controlling fluid flow through said other of said pair of passageways.

3. In a pressure-operated ram mechanism, a platelike base having a platelike portion extending laterally thereof, said portion having an aperture opening through one face thereof, a cylindrical member having a portion held within said aperture, said cylindrical member having a piston chamber therein opening through one end wall thereof and having a pair of passageways opening outwardly through another wall thereof,

one of said passageways communicating with said chamber adjacent one end thereof, said cylindrical member having a reduced diameter outer peripheral portion, the other of said pair of passageways communicating with said peripheral portion, a piston having a head portion positioned within said cylindrical member and having a hollow stem portion extending outwardly of said end wall, an adapter, means securing said adapter to said stem portion, a sleeve telescoping over said cylindrical member, one end of said sleeve being secured in fluid tight relationship to said adapter to form a pressure chamber, the other end portion of said sleeve extending beyond said peripheral portion to form an outlet chamber and toward the other end portion of said cylindrical member whereby said sleeve is guided at spaced points for reciprocal movement longitudinally thereof, said cylindrical member having a passageway leading from said piston chamber adjacent said cylindrical member one end wall and opening into said outlet chamber, means surrounding said stem portion intermediate said last-named passageway and said cylindrical member one end wall and co-operable with said cylindrical member to guide said stem portion, said stem portion having a passageway opening from

10
15
20
25

the hollow interior thereof and positioned longitudinally of said stem portion so that at one position of said piston said stem portion passageway opens into said outlet chamber, the longitudinal position of said stem passageway being such that upon movement of said piston in one direction said stem portion passageway is closed by said surrounding means, and means for conducting fluid from the portion of said piston chamber which is intermediate said head portion and said chamber one end to the hollow interior of said stem portion, said stem portion having a fluid flow passageway leading from its hollow interior to said pressure chamber.
